UNITED STATES PATENT OFFICE.

JOHANN DIEDRICH GEORG OHLHAVER, OF HAMBURG, GERMANY.

CENTRIFUGAL-SEPARATOR LINER.

SPECIFICATION forming part of Letters Patent No. 635,579, dated October 24, 1899.

Application filed June 28, 1899. Serial No. 722,136. (No model.)

To all whom it may concern:

Be it known that I, JOHANN DIEDRICH GEORG OHLHAVER, of Hamburg, Germany, have invented a new and useful Improvement 5 in Liners for Centrifugal Separators, of which the following is a specification.

In centrifugal cream-separators the separation is effected in a radial direction. In all bowl-liners for centrifugal cream-separators it 10 has therefore been considered that the separation is most favorably effected when the milk to be separated is divided into thin layers in such a way that a radius drawn from the axis to the periphery of the bowl intersects as many 15 of such layers as possible in order to shorten the path of the separation, and for this reason conical, cylindrical, prismatic, spiral, or the like partitions have been proposed for insertion. In my improved liner, on the contrary, the milk is not divided radially into 20 layers. Experience has shown that the separation is most favorably effected when the angular velocity of the bowl is rapidly imparted to the milk, when the currents in the bowl are suitably diminished, and when the vibrations of the liquid are removed as far as 25 possible. My improved liner completely fulfills these conditions.

It consists of perforated, cut, or punched 30 horizontal partitions *a*, with radially-extending vertical projections *b*. Instead of this the liner can also consist of a combination of radially-extending vertical disks with perforated, cut, or punched horizontal partitions, 35 which are arranged alternately one above the other. The horizontal partitions *a* must allow the liquids to go through them and have

therefore to be perforated, cut, punched, or otherwise provided with holes *a'* or must consist of sieves with close meshes. It is of advantage to provide the outer edge of the horizontal partitions with a narrow vertical rim *c*. It is not necessary that the radially-extending projections *b* stand at right angles to the horizontal partitions *a*, as they may form any suitable angle with said horizontal disks. The radially-arranged projections *b* may be mounted directly on the horizontal sieves or perforated, cut, or punched horizontal plates *a*, or these projections may form separate radially-arranged vertical disks. These radial projections *b* may also be continuous walls running from top to bottom, in which the horizontal sieves or perforated, cut, or punched disks *a* are inserted. 55

A form of construction of the liner is shown in Figures 1 and 2 of the accompanying drawings in vertical section and plan.

The form of construction is arranged in each case to suit the actual circumstances. 60

Having now particularly described and ascertained the nature of my said invention and in what manner the same is to be performed, I declare that what I claim is—

In a liner for the rotating bowl of a centrifugal separator, the combination with the perforated horizontal partitions, *a*, narrow vertical rims *c*, and vertical partitions *b*, substantially as herein shown and described. 65

JOHANN DIEDRICH GEORG OHLHAVER.
